UNITED STATES PATENT OFFICE.

CHARLES P. LOUGHridge, OF NEVADA, CALIFORNIA.

DESIGN FOR A MEAT-HOLDER.

SPECIFICATION forming part of Design No. 27,018, dated May 4, 1897.

Application filed March 25, 1897. Serial No. 629,283. Term of patent 14 years.

To all whom it may concern:

Be it known that I, CHARLES P. LOUGHridge, of Nevada city, in the county of Nevada and State of California, have invented 5 and produced a new and original Design for a Meat-Holder, of which the following is a full, clear, and exact description.

Reference is to be had to the accompanying drawing, forming a part of this specification, 10 in which the figure represents a perspective view of a meat-holder embodying my new design.

The design in its entirety comprises an elongate member A, a transverse member B adjacent to one end, a second transverse member C, ranging across the elongate member intermediate its ends, and the pin-like member D, standing out at an angle to the elongate member and adjacent to the second trans- 15 verse member, and the several features are 20 in detail as follows, to wit: The elongate member A has at one end an eye a. The transverse member B, which is at the end opposite the eye a, has its ends turned in opposite directions, as at b b', and at the junction of the 25 arms of the member B with the elongate member A there appear, respectively, a single twist

b² and a double twist b³. The member C at one side of the elongate member A has its end c turned in the same direction as the corre- 30 sponding end b' of the first transverse member B, and at the opposite side of the elongate member A the member C has a U form. At the junction of the members A and C twists c c² appear, and adjacent to the said member C a pin-like member D stands out 35 at about right angles to both the members A and C.

The leading feature of the design comprises an elongate member, a transverse member 40 ranging across the elongate member adjacent to one end thereof and having its ends turned in opposite directions, a second transverse member intermediate the ends of the elongate member, and a pin-like member standing at 45 about right angles to the elongate member and to the second transverse member.

I claim—

The design for a meat-holder herein shown and described.

CHARLES P. LOUGHridge.
